GAS APPARATUS.

Application filed November 22, 1924. Serial No. 751,538.

This invention relates generally to the production of gaseous fuels and to an apparatus therefor.

There are various types of gaseous fuels manufactured and distributed for domestic and industrial purposes, and also used at the places where they are made. These types of gaseous fuels may be divided into two great classes, according to whether or not the apparatus in which they are manufactured is heated internally or externally. Thus, coal gas is a fuel gas which is made by the distillation of coal in apparatus that is heated externally, while both water gas and producer gas are manufactured in apparatus wherein the heating takes place internally. Generally the manufacture of such gaseous fuels is accomplished in apparatus which is particularly designed for the purpose, although in the manufacture of producer gas, it is customary to introduce steam and thereby control the temperature within the producer, with the result that a certain amount of water gas is made along with the producer gas. However, in the manufacture of water gas itself, an apparatus is used which is especially designed for that purpose.

Where I have tried to recover distillation products from carbonaceous material and by means of one single apparatus manufacture coal gas, blue gas, carburetted blue gas, producer gas, I have found that the progressive changes in volume of the carbonaceous matter taking place, beginning with the raw material up to complete reaction, are such as to render the gas generating apparatus, as presently designed, incapable of operation in this fashion without clogging up of the apparatus and disturbance of the reactions that take place therein.

The object of my invention is to accomplish the manufacture of a mixed gas by a combined external and internal heating of the carbonaceous fuel. Furthermore this invention resides in the complete gasification of the raw fuel, so that the principal product is gas containing but little tarry matter and ammonia vapors, in which process no coke

is produced and the final product is merely ash or clinker.

Another object of my invention is to provide a means for the complete gasification of coal and other carbonaceous fuel which will be available to the small gas plant. The present systems devised for the complete gasification of coal are unavailable to the small gas plant for the simple reason that the manufacturing capacity of these systems is far greater than what is required in such gas works.

Another object of my invention is to manufacture a mixed gas of varying thermal capacity, providing a means to enable the gas works to control the calorific value of the gas. Thus it is possible for the gas works that employs this invention to make gas suitable for various needs in one and the same apparatus.

Still another object of my invention is to provide a means for the recuperation of the heat developed in the internal combustion of the fuel within the generator, and to use this recuperated heat for the external heating of that part of the apparatus wherein distillation of the fuel takes place. Thus, it is possible in one and the same apparatus to distill coal, to make water gas by the reaction between hot incandescent carbon and steam, and producer gas by the usual method of blowing air through a bed of incandescent carbonaceous matter.

In order to carry out this invention I have devised an apparatus which is described herein in detail, and which is one preferred method of carrying out my invention.

The construction of the improved gas apparatus, in its preferred form, is illustrated in the accompanying drawings, of which:

Fig. 1 is a vertical longitudinal section of the apparatus; and

Fig. 2 is a plan view of the apparatus.

In the drawings, 1 designates the gas generator, and 2 the regenerator which is built around the generator uniting with the latter to form a unitary construction. The shell 3 of the gas generator 1, is made of iron, and is lined with fire-brick 4. The shell 5

of the regenerator is also made of iron, and is lined with fire-brick 6. At the bottom of the gas generator 1, there is an inlet 7 for steam, and another inlet 8 for air, and an outlet 9 for the removal of the clinker which collects on the grate 10. Another outlet for the removal of the clinker and ash dropping through the grate is provided at 10A.

10 An outlet 11 controlled by a valve 11A is provided for the discharge of water gas during the down run operation of the apparatus. The main body of hot, carbonaceous fuel in the generator is seen at 12, and the coal in progress of distillation is shown at 13. The suction pipe connection is seen at 14. At the top of the carbonizing retort is the charging door 15; 16 is the outlet for the coal gas; and 16A is the pipe leading 20 this gas to the water seal 17, from which the gas passes to the exhauster 18, and thence eventually through the pipe 32 to a gas purifying plant (not shown). The regulator and steam engine driving the exhauster are not 25 shown, being standard apparatus.

The regenerator 2 is filled with checker-work 19, and the lower end is provided with air inlets 20 and 21, which are controlled by valves 22 and 23. The air blast 30 is passed through pipe 26A, dividing and passing through pipes 25A and 24A, the former connected with the air inlet 8, and the latter with the inlet 21. The air inlet 20 is also connected with the main blast 35 line, the connection not being shown on the drawing. A blue water gas outlet 27 controlled by the valve 27A opens from the regenerator at its top as do the stack valves 25 and 26.

40 A pipe 31 connected to the gas outlet 16, a pipe 28, a water seal 29, a pipe 30; and another 31A, connected by a regulator to the pipe 32 leading to a purification plant, forms a by-pass for water gas, about the 45 seal 17.

The exhauster 18, is driven by a standard type of steam engine (not shown in the figure), and is itself connected through the pipe 14, with the interior of the carbonizing 50 retort section of the apparatus; in other words, that part of the apparatus which is surrounded by the heat regenerator. In this way the speed of the exhauster is controlled, so that a definite suction is always 55 maintained in the aforementioned carbonizing section of the gas producing apparatus.

The advantages that are gained by the use 60 of this especially designed gas apparatus are many, and I will describe in the following the most important of these advantages as compared with gas generators and gas producers as they are now constructed and used.

A distinctive feature in the design of the 65 new gas apparatus, and one which I claim

particularly as novel and important, is the construction of the gas generator or reaction chamber, essentially in three parts or sections A, B and C. The lower part A of the generator is cylindrical in form, having a vertical wall. This part of the generator is approximately 9 feet high, and I prefer to make it that height although its exact dimensions are not an essential feature of my invention. Accordingly, I do 75 not limit myself to such dimensions as mentioned above, or hereinafter described, but have chosen these, that are given herein, as being the preferred form for my purpose, and which I describe by way of illustra- 80

85 Preferably the lower vertical part A of my generator connects directly with the intermediate section B which is in the form of a hollow, truncated cone. This intermediate section is about 8 feet high. The intermediate section B joins on to the top section or part C which is 4 feet high, and which is also in the form of a hollow truncated cone, but the conical angle of the section C is greater than the conical angle of the section B.

90 Thus, the generator comprises a cylindrical and two truncated cone sections, the latter having sides of different inclination. The total height of the apparatus is 21 feet.

95 The purpose of making the generator of this form is to secure an even distribution and uninterrupted downward flow of the carbonaceous fuel which is introduced into the generator at the top. This is made possible by sloping the sides of the carbonizing retort formed by the sections A and B with inclined side walls as described above, so that the coal that is introduced slides 100 down along the inclined side walls, and as this action takes place, is subjected to distillation through the transmission of heat from external sources through the walls of the generator. Such easy, free, unhampered 105 motion of the fuel, in spite of the increase in volume occasioned by tumefaction, is impossible in producers and gas generators of ordinary design, for the reason that the swollen mass of coal binds against the walls 110 of the apparatus and results in its clogging up, so that operation must be interrupted and the apparatus cleaned out before it can be resumed. While it is preferred to make the upper portion of this gas generating 115 apparatus in two sections, as described heretofore, it is also possible and advantageous to make this sloping portion of the generator in multiple sections, three or more in number. In fact it has also been found to be 120 advantageous to increase the number of these sections infinitely and make the upper portion of the generator in the form of a dome.

125 The same advantageous results are obtained thereby as hereto and hereinafter de- 130

scribed. It is thus my purpose not to limit the scope of this invention to a generator with two sloping upper sections, this being merely one of many ways in which the upper portion of said generator may be constructed within the meaning of the above.

Another important feature of this new apparatus arising from its construction, as heretofore described, is that the fuel, after being introduced at the top of the apparatus, is distributed in a thin annular layer around a central mass of hot carbon, the width of this annular layer gradually decreasing as the coal descends along the sides of the carbonizing retort. In this way it is possible to carbonize the fuel by the transmission of heat from external sources through the walls of the carbonizing retort, such carbonization taking place in such a manner that by the time that the fuel has reached approximately the beginning of the vertical section of the apparatus, all the volatile matter that was originally contained in it has been distilled.

It has also been found in operating this type of gas apparatus that carbonization will take place quicker than in the ordinary apparatus, and the capacity of the apparatus will be considerably greater than one of another design which possesses the same cubical volume.

Still another advantage of this apparatus is the fact that the hydrocarbons, comprising the volatile matter in the carbonaceous fuel used therein, are given an opportunity not only to be distilled over in the form of vapors, but also to be converted into the state of a fixed gas by coming in contact with the hot masses of carbon in the central portion of the generator. This naturally results in the production of a gas of higher thermal value than would otherwise be obtained.

An additional feature of my invention, but which it is not intended to be claimed as original in itself, but only so far as it applies to the apparatus which is described and claimed hereinafter, is the heat regenerator which surrounds the non-vertical sections of the generator. This regenerator is made in the usual form and serves to store heat during a certain stage of the operation of the apparatus, which heat is afterwards employed for the distillation of the coal that comes in contact with the hot inclined walls of the carbonizing retort. The regenerator makes the inclined section of the apparatus in reality a sort of retort and enables the manufacture therein of a type of coal gas which is ordinarily not obtained when using the common type of gas generators.

This arrangement, therefore, enables the manufacture not only of blue water gas, producer gas, but also of a coal gas, resulting in a mixed gas containing varying proportions

of all three. It is also possible by using the heat accumulated in the recuperator for cracking gas oil, introduced therein and sprayed upon the hot checkerwork, to produce thereby a carburetted water gas as well.

Another feature of this apparatus is a means for controlling the suction within the producer by transmitting the suction developed therein through a suitable pipe, connecting the same with a regulator, either of a standard type for controlling the introduction of steam into a steam engine driving the exhauster, or of the rheostat type for regulating the speed of an electric prime mover driving the exhauster. In this manner it is possible to maintain the proper suction within the inclined sections of the apparatus, so that the flow of gas that is manufactured therein will be diverted into the proper outlets and not permitted to escape into the recuperator which is connected with the interior of the generator. If this did take place, the hydrocarbons in the gas would be decomposed and lost. It is noted that the connections between the generator and the regenerator cannot be closed by valves. The particular type of controlling device used in regulating the speed of the exhauster, so as to obtain the proper suction, is not an essential part of this invention, and any suitable arrangement may be used for this control.

In operating the new type of gas producing apparatus, herein described, the fuel, which may be either soft coal, hard coal, coke or other carbonaceous matter, is charged through the charging door, 15, and is filled into the apparatus, as is shown in the accompanying figure. After the coal is put into the apparatus, the charging door is closed and a fire is built in the bottom of the generator and the coal is set on fire. A blast of air is then permitted to pass through the burning coal by opening the valve 23A. The stack valves, 25 and 26, are then opened, the coal heated, and the producer gas, which is formed during this process of blasting, passes up through the openings, 20A and 20B, and thence up through the checkerwork of the regenerator surrounding the retort section of the apparatus. Air is also admitted to the regenerator through the valves 22 and 23, and the producer gas mixed with air is burned in the regenerator, so that the checkerwork is heated up to a high temperature, and this in turn heats the retort section of the apparatus. The products of combustion that are formed during this operation leave the regenerator through the stack valves 25 and 26.

During this operation of heating up the retort section of the apparatus, the coal which is in the retort is gradually heated up as well and a certain amount of hydrocarbon gas is distilled off and escapes through the coal gas outlet 16, and pipe 16A. The heat-

ing of the coal in the lower part of the generator during the air blasting process converts it into coke and generates producer gas in the regular manner. When the retort 5 section of the generator has been heated up to a high enough temperature in this way, the blasting process is discontinued. The stack valves, 25 and 26, are closed and the blast of air is shut off by closing the valve 10 23A. The valves 22 and 23 are also closed and the apparatus is now ready for the manufacture of water gas. The exhauster, which runs continually and draws off the coal gas, while the air blasting is being carried on, is continued in operation, while 15 steam is then admitted through the opening, 7, at the bottom of the apparatus. This steam passes into the apparatus under the grate bars, makes its way through the incandescent coke, produced as has been indicated during the air blasting process, and acting on this incandescent carbon, forms 20 water gas.

While the exhauster is allowed to draw 25 the gas out of the apparatus, the water gas passes up through the retort section of the apparatus, where its temperature is considerably raised. Furthermore, this gas in passing through the decomposing coal in 30 that section of the apparatus, helps to carbonize the same and also assists in carrying off the hydrocarbons and tarry vapors distilled from the coal.

As has been described, the speed of the 35 exhauster is controlled by means of a regulator, which is itself controlled by the suction which is maintained in the retort section of the gas apparatus. However, the exhauster is not able to remove all the gas 40 that is formed in the apparatus, as water gas is made at a considerably greater rate than coal gas. The result is that the excess water gas passes through the pipe, 31, the by-pass 28, the water seal 29, and pipes 30 45 and 31A, and eventually is mixed with the gas drawn off by the exhauster and passes to a purification plant through the main 32.

Under certain conditions it is desirable to 50 make a blue water gas containing no hydrocarbons, but practically all carbon monoxide and hydrogen. In this case the apparatus is operated in a similar manner, as described above, with the exception that the exhauster is shut off, and blue water gas is 55 allowed to pass through the openings 20A and 20B into the regenerator, and finally out through the water gas outlet 27, which is controlled by the valve 27A.

As the carbonaceous matter is being 60 burned up in the gas generating chamber, fresh supplies are charged in at the top from time to time. This fresh coal fills the space between the carbonized coal and the retort. This space is formed by the downward 65 movement of the carbonaceous matter in the

retort. Under ordinary operating conditions the mass of coal will move down with a rate of approximately twelve inches per hour. As the entire mass gradually goes down together, an annular space is left in the 70 upper chamber about five inches thick at the top, tapering to one inch or two inches thick at the bottom of the inclined sections. It is this space which is filled by the fresh coal when the latter is charged into the 75 generator.

This method of operation results in the fresh coal being subjected to distillation, the heat for the same being obtained from the accumulated heat in the checkerwork of 80 the regenerator surrounding the retort. In other words the fresh coal fed to the apparatus is subjected to the same distillation as that which takes place in an ordinary inclined, vertical or horizontal retort. 85 During this operation the coal gas is manufactured. This gas is drawn out of the apparatus by the exhauster 18.

When the regular water gas run is finished and the steam is shut off, the exhauster, 90 which has been running constantly during this part of the process, immediately goes back to normal suction. The charging door is then opened, and a fresh supply of coal is charged into the retort. By this time, as 95 well, the heat in the regenerator has been entirely used up, and it is therefore necessary to reheat the regenerator. This is accomplished in the same manner as has been described above. Thus the heating of the 100 regenerator and the formation of gas in this apparatus is discontinuous. The ash and clinker that are formed during these operations are periodically removed through the openings 9 and 10A.

It is also possible to make a gas of a low 105 thermal value in this apparatus. In order to do so water gas is not made, but a small amount of steam is admitted under the grate sufficient to prevent its burning out. Air 110 is drawn through the hot carbonaceous matter, and a producer gas is made which passes up through the retort and is mixed with the hydrocarbons which are distilled from the coal, coming in contact with the hot walls of 115 the retort. In this way there is made a producer gas of rather higher heating value than is otherwise possible. Thus it is possible in this apparatus to make either blue 120 water gas, producer gas, coal gas, or carburetted water gas, the latter being made by spraying oil into the regenerator and on to the checkerwork therein, using a standard 125 type of spraying device.

Means are also provided for making down 130 runs of the apparatus, as is customary in water gas practice. In this case steam is admitted through the opening 24 in the regenerator, passed through openings 20A and 20B, through the mass of coal in the lower 135

part of the generator, and the water gas that is produced in this process is allowed to flow out through opening 11 at the bottom of the generator.

5 Having thus described my invention in full detail, I claim the following:—

1. Gas apparatus comprising a vertical reaction chamber having its upper portion tapered so that it progressively increases in 10 cross section from the top toward the bottom, and provisions, including means for feeding fresh fuel into the top of the chamber and for externally heating the upper portion of the chamber, for maintaining a carbonizing zone in the upper portion of the chamber and a gasification zone in the lower portion of the chamber and characterized by 15 the fact that the uppermost portion of said chamber is more sharply tapered than the 20 subjacent portion.
2. In apparatus for the complete gasification of carbonaceous material, the combination comprising a vertical reaction chamber consisting of an upper retort section and 25 a lower gas generating section, fuel charging means at the top of the retort section, waste material discharging means at the bottom of the generating section, and a regenerator surrounding said retort section, said 30 retort section having two sloping portions, the top portion possessing a greater slope than the lower portion, and the cross-sectional area of said portions increasing from the top towards the bottom.
3. In apparatus for the complete gasification of carbonaceous material, the combination comprising a vertical reaction chamber consisting of an upper retort section and a lower gas generating section, external 35 heating means for said retort section, fuel charging means at the top of said retort section, waste material discharging means at the bottom of said generating section, said retort section being made in multiple sloping 40 portions, the slopes of said portions increasing with their elevation, and the cross-sectional area of said portions increasing from the top towards the bottom of said retort 45 section.
